UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,172,485.

Specification of Letters Patent. Patented Feb. 22, 1916.

Application filed March 9, 1914. Serial No. 833,399.

To all whom it may concern:

Be it known that I, FRANK C. RINSCHE, a citizen of the United States, residing at Detroit, in the county of Wayne and State of Michigan, have invented certain new and useful Improvements in Adding-Machines, of which the following is a specification.

The present invention relates to tabulating equipments for adding machines and therefore has to do more especially with the recording function of such machines which, though commonly spoken of as adding machines, usually combine both adding and printing functions. In late years there has been considerable development of such machines along tabulating lines with the object of extending their use to tabulation upon a wide sheet of paper.

The general aim of my present invention is to so equip the machine as to enable the user to more conveniently and expeditiously vary the order of tabulation to suit the particular work in hand or to suit his particular manner of handling the work, and at the same time to provide an equipment adaptable to existing types of machines in commercial use.

I have chosen to here disclose my invention in concrete form as applied to the well-known Burroughs' machine. I am aware that there have been numerous applications of tabulating equipments to this machine and that tabulating functions in connection with its use have been already developed to a high degree. It may be useful at this point to make specific reference to several prior patents which will serve to indicate the state of the art in this regard. Patent No. 913,738 issued March 2, 1909 upon the invention of Oscar C. Kreis, Patent No. 929,056 issued July 27, 1909, upon the invention of Jesse G. Vincent, Patent No. 988,700 issued April 4, 1911, upon the joint invention of Harvey L. Fisher and Jesse G. Vincent, and Patent No. 1,028,133 issued June 4, 1912, upon the invention of Heber C. Peters, all appertain to tabulating arrangements applied to the Burroughs machine and involve the use of a spring to impel the carriage from column to column under control of stops, not manually governed as by one or more tabulating keys, but automatically governed through connection with the prime mover of the machine proper, though

manipulation of a handle or knob on the paper carriage may serve in these prior constructions for manually setting the carriage in any desired columnar position. In all of said prior constructions return of the carriage, or back shift against the tension of the impelling spring, was effected by direct application of the hand of the user to some part of the paper carriage.

Patent No. 924,118 issued June 8, 1909 upon the joint invention of Jesse G. Vincent and Russell E. Benner and Patent No. 1,048,249 issued December 24, 1912, upon the invention of Nelson White, afford examples of tabulating equipments applied to Burroughs machines and involving automatic reciprocation of the paper carriage between two columnar positions in successive operations of the machine, the carriage being driven first one way and then the other through geared connection with the prime mover of the machine proper. Patent No. 977,582 issued December 6, 1910 upon the invention of Edward R. Barrett, and Patent No. 1,046,546 issued December 10, 1912 upon the invention of Russell E. Benner, show tabulating equipments which provide for columnar shift of the carriage from right to left in an automatic manner akin to that characteristic of the first mentioned group of patents, and also show machines for automatically returning the carriage upon operation of the machine to record with the carriage in the last of its columnar positions,—the carriage being thereupon returned to its first columnar position. The latter type of equipment is of course admirable for expediting preordained tabulation which calls for repeatedly recording horizontal series of items and solid vertical listing in column after column.

My present invention aims to take care of a somewhat different sort of tabulation and a greater variety of work and I find it advantageous, in furtherance of this object, to revert to a manual and somewhat less automatic control of the paper carriage which will permit the user to vary the order of tabulation at will, as by either causing the carriage to move to the left from one columnar position, past one or more intervening columnar positions, to one farther over to the right, or returning or back-shifting the carriage from an intermediate columnar po-

sition to the extreme left-hand position or from the extreme right-hand position to any intermediate columnar position. Such manipulation is possible with the semi-automatic equipments of the group of patents first specifically mentioned but it involves application of the user's hand to various parts of the paper carriage. My invention provides for greater convenience and increased dexterity of manipulation by providing a crank handle or hand lever at the left-hand side of the machine proper, having a path of travel at right angles to that of the paper carriage (the same as does the familiar operating handle located at the right of the machine proper) which handle is within easy reach of the user when seated in front of the machine. Such handle is geared to the paper carriage and moves with it and may serve merely as a convenient and effective means for back-shifting the carriage, or it may serve in conjunction with adjustable stops (ranging along the left side of the machine proper and thus readily accessible for purposes of adjustment) for tabulating purposes in place of stop fingers such as customarily carried upon a rock rod of the paper carriage and coöperating with a fixed stop at the back of the machine. I also provide a tabulating key whereby the carriage may be caused to move from a left-hand columnar position over to a right-hand columnar position passing by, without stopping at, one or more intermediate columnar positions.

In several of the prior art tabulating equipments of the above mentioned patents, provision is made for bringing into action the line-spacing mechanism at some predetermined columnar position of the carriage (for example, in the structure of the Benner Patent No. 1,046,546 the line-spacing mechanism is brought into action during operation of the machine with the carriage in the last or extreme right-hand columnar position). The line-spacing in question is a part of the operation of the machine, and therefore is not available in connection with such shift of the paper carriage backward or forward as done through the use of the special equipment of my present invention, since there is no accompanying operation of the machine proper. Hence I make special provision for line-spacing independently of any operation of the machine proper. Thus I provide for line-spacing as a result of back shift of the carriage, and I also provide for line-spacing through use of the same key which serves for wide tabulation as above mentioned.

I am aware of the highly developed state of the art as represented by Patent No. 1,063,181 issued June 3, 1913, upon the invention of John J. Chapin, which shows a

tabulating equipment providing for automatic shift of the carriage in either direction from any columnar position to any other as the result merely of depressing the appropriate key of a series of tabulating keys arranged at the left-hand side of the machine. As contrasted with the tabulating equipment of this Chapin patent, the tabulating equipment of my present invention is designed for application to the standard Burroughs broad-frame paper carriage adding and listing machine, with the minimum of change in the regular construction thereof, my equipment being in the nature of a comparatively simple attachment to the machine, which attachment is itself of a readily manufacturable character besides entailing no complication with respect to assemblage with the regular parts of the machine. Furthermore, it is of such a character as to permit of the customary automatic stepping of the carriage from column to column in successive operations of the machine if that mode of operation is desired, the tabulating key in such case being simply left alone and the carriage crank handle or hand lever being employed merely as a means for throwing the carriage back to the right, i. e., the special tabulating stops not being set in position to coöperate with this crank handle or hand lever.

Of the drawings which accompany and form part of this specification, Figure 1 represents in left side elevation, a machine of the Burroughs type having applied thereto certain of the devices hereinafter specifically described which serve for carrying out my invention; Fig. 2 shows the machine partly in top plan view and partly in horizontal section; Fig. 3 is a left side elevation on an enlarged scale of the carriage crank handle and associated parts together with a portion of the paper carriage in vertical section the handle being reversed in position as compared with its position in Fig. 1; Fig. 4 is a vertical cross section on the line 4—4 of Fig. 3; Fig. 5 is a top plan view of the crank handle guiding and indexing structure including tabulating stops, the mounting of one of which is sectionalized; Fig. 6 is a fragmentary cross section on line 6—6 of Fig. 3; Fig. 7 is a fragmentary horizontal section taken on line 7—7 of Fig. 3; Fig. 8 shows the machine in rear elevation with some parts broken away to better disclose others farther forward; Fig. 9 is a vertical section taken substantially on the line 9—9 of Fig. 8; Fig. 10 is a fragmentary perspective view of special line-spacing devices; Fig. 11 is a right side elevation of the machine with its casing partly broken away and sectionalized; Fig. 11^a is a detail perspective of a special pawl-carrying lever and pawl; Fig. 12 illustrates a machine in left side elevation with a modified form of

carriage crank handle and gear connection; Fig. 13 is a fragmentary top plan view of the same.

No detailed description of the machine proper is necessary to a thorough understanding by any one skilled in this art of the adaptation of the present improvements to the Burroughs machine. The latter is well known through extensive commercial use and through disclosures of numerous prior patents. Furthermore, the paper carrying equipment at the rear is now so well known as to require but brief mention, the same being of a character closely resembling those of the above mentioned prior patents, more especially the patents of Kreis, Vincent, Vincent and Benner, White, Barrett and Benner. This has reference to the mounting of the carriage for lateral shift across the back of the machine, the use of a double spring drum 2 for propelling the carriage from right to left, and the employment of a rocking tabulator rod 3 having fingers 4 adjustably secured thereon for determining columnar positions of the carriage through co-operation with a fixed plate 6. The normal line-spacing mechanism is also of similar character comprising plates 7 and 8 with jaws 7^a and 8^a embracing a bail cross rod 9, the plate 7 being reciprocated in every operation of the machine by a lever 10 vibrated by a cam 100^a secured to the familiar rock shaft 100. A laterally displaceable spring held dog 7^b is pivoted upon the plate 35 7 and formed to engage over a shoulder of the plate 8 for the purpose of drawing the latter down with the plate 7. The upper end of this dog is adapted to act upon the fingers 4 to disengage them from the stop plate 6. This provides for columnar shift 40 of the carriage in a familiar manner and it is customary to control the dog as to lateral displacement so as to provide for connection and disconnection of the plates 7 and 8 as 45 line-spacing may be desired or not in the progress of the tabulated work.

In the present instance the aforesaid double spring drum is geared to the carriage, the latter having secured along its 50 upper portion, on the side toward the machine proper, a rack 11 and there being secured to the upper member of the drum a gear wheel 12 which meshes with said rack. Similar gearing appears in the Barrett Patent No. 977,582 and its purpose is to provide for propelling the carriage in either direction by the turning of the drum as contrasted with the familiar arrangement of a band or tape winding upon the drum and attached to the 55 carriage. In carrying out the present invention said gearing is availed of in connection with the crank handle or hand lever located at the left side of the machine.

Referring first to Figs. 1 to 9, the hand 60 lever is designated by the numeral 13, the

same being journaled at its lower end upon a frame stud 14 and carrying a gear segment 15. The latter is in mesh with a similar segment 16 which is part of a lever 16^a pivoted upon a frame stud 17 and formed at 70 its upper end with an extended gear segment 16^b. This latter segment is in mesh with a spur gear 18 secured to a short shaft 19 to which is also secured a bevel gear 20 meshing with a similar gear 21 fastened to the 75 drum gear 12. Owing to the character of the lever 16^a and segment 16^b, the latter is arranged to run between disks 18^a at opposite sides of the spur gear 18 so as to preserve the alinement.

Obviously the geared connections above pointed out between the carriage and the handle will cause these parts to move together,—the handle moving rearward as the carriage shifts to the left, according to the 85 construction now under consideration, and, correspondingly, the carriage being driven to the right by forward pull upon the handle.

Assuming such equipment of the carriage 90 for tabulating purposes as has already been pointed out, and further assuming employment of the hand lever without special tabulating stops to be described later, it will be clear that the machine can be operated in 95 the usual manner for tabulating purposes with the automatic shift from column to column as the dog 7^b successively disengages the fingers 4 from the stop plate 6. This would have the effect of swinging the hand 100 lever 13 rearward step by step from the position shown in Fig. 1 to the position shown in Fig. 3. Then by pulling the handle forward the carriage would obviously be driven back to the right. The hand lever projects 105 up past an index holder in the form of a curved plate 22 fastened to the casing of the machine and flanged to hold cards or slips 23. These may be inscribed according to the 110 character of work and located in the guideway at positions corresponding with the columnar positions of the carriage as determined by the stop fingers 4. Referring to Fig. 5, it will be noted that the slips bear 115 inscriptions appropriate to bank work. This enables the user to determine at a glance where the carriage is located with respect to the tabulation. Obviously the handle can be employed at any time to throw the carriage back to the right, without its having necessarily shifted all the way over to the left, so that the user can employ any limited 120 number of columnar positions of the carriage. This was of course equally true of the former arrangement such as that shown in the Vincent Patent No. 929,056, leaving out of consideration the special handle and connections for facilitating the operation. However, the matter of line-spacing comes 125 into consideration for, if under the old ar-

arrangement the carriage is thrown back to the right before the limit of shifts to the left has been reached, there is not the automatic coupling of the line-spacing devices. According to the present invention instead of having the line-spacing depend upon the carriage arriving at the last of a series of columnar positions, I provide for line-spacing as a result of the return of the carriage to its first columnar position, and I make use of the rock rod 3 in this connection. In order to effect line-spacing by said rock rod it is moved in excess of the movement given to it for tabulating purposes. For this purpose there is fastened to said rod near its left-hand end a special finger 24 (Fig. 10) formed with a beveled head 24^a to ride over the bevel 25 of a blade 25^a located adjacent the back plate of the machine. In restoring the carriage in opposition to its spring, it will be driven beyond the initial columnar position, so that the beveled head of said special finger will ride completely over the bevel 25 of said blade and thus the rod 3 will be rocked in excess of the movement it has for tabulating purposes, which excess movement through connections presently to be described, effects a single line-spacing. Then the carriage is returned by its spring to the initial columnar position. In order to provide for displacement of the blade to permit this proper repositioning of the carriage, said blade is given a right-angle twist so that a middle portion may stand in between the vertical sides of a pivot block 27 fastened to the back plate of the machine. The blade is pivoted in this block and a spring 28 inserted between it and the base portion of the latter, normally throws the upper part of the blade rearward as limited by abutment of a forwardly projecting under portion 25^b against the back plate of the machine, all as clearly shown in Fig. 10. The shoulder 25^c which terminates the bevel 25 is itself beveled so that the end of the head 24^a will operate against it upon shift of the carriage to the left and thereby displace the blade so that the finger 24 may pass by the same. An extended upper edge of the blade at the base of the beveled shoulder 25^c prevents the finger head 24^a from dropping too far. Then the blade stands so close to one of the studs supporting the fixed stop plate 6 (Fig. 8) that overrunning of the carriage would cause the head 24^a to ride up on said stud and thus be prevented from dropping below the line of the beveled surface 25^c. The above described excessive rocking of the tabulating rod 3 does not effect line-spacing through the connections previously described, which connections ordinarily serve for line-spacing, except that the same platen ratchet wheel 30 is operated upon.

Referring to Fig. 11 there is secured to the right-hand end of said rock rod an upstanding arm 31 having a stud occupying the bifurcation of an arm 32 of a rocking structure comprising in addition to said arm 70 a yoke piece 33 and an arm 34 to which is pivoted a pawl 35 (Fig. 11^a). The said rocking structure is pivoted upon an extension of the rock rod 5 of the aforesaid bail having the cross rod 8. A spring 36 75 connects the arm 32 with a stud on the end of the carriage and serves to normally retract the pawl 25 besides serving to maintain the normal position of the tabulator rock rod. Another spring 37 connects the 80 pawl 35 with the yoke portion 33 of the rocking structure so as to press the pawl into engagement with the ratchet though normally this is prevented by contact of the pawl with a collar on the shaft 40, the latter being a familiar element of the paper carriage used for retracting the feed rollers when the paper is to be adjusted. Preferably there is formed integral with said pawl an overthrow-preventing tooth 35^a which enters between teeth of the usual V-toothed wheel 42 on the platen. Referring to the matter of effecting the shift of the carriage to the left otherwise than as an incident to operation of the machine, the reference numeral 50 designates a key located at the front of the keyboard preferably off to the right, said key being coupled to a link 51 (Fig. 11), and suitably guided by a frame stud 52 engaging 95 a bifurcated lower member of the key stem. The link 51 is coupled to the forwardly extending arm 53 of a lever pivoted at 54 to the right-hand frame piece of the machine and having a rearwardly extending 100 arm 55 which protrudes through a slot in the back plate of the machine and extends under an arm 56 (Fig. 8). This arm extends transversely across a portion of the back plate of the machine and is rigidly 110 connected with another arm 57, the two arms forming a lever pivoted at 58 to said back plate. The arm 57 extends up in rear of the tabulator rock rod 3 and has a rearwardly projecting roller stud 59 at its upper 115 end overlying the cross bar 60 of a bail which rocks with said rod. This bar 60 is secured to arms 61 fastened to said rock rod. A spring 63 (Fig. 11) applied to the forwardly extending arm 53 of the first men- 120 tioned lever normally upholds the key 50. Depression of the latter will obviously rock the lever 56—57 and thereby rock the bail and consequently the rod 3 and thus cause the carriage to shift. The aforesaid key 50 125 is also available for optional line-spacing. Its depression above referred to is not its full depression for it will be recalled that the rod 3 is capable of excessive rocking for line-space purposes. Therefore further de- 130

pression of the key 50 can be caused to effect line-spacing by the same degree of rocking of the rod 3 as that produced through the before described co-action of 5 the special finger 24 and the blade 25. No special indexing of the key 50 is required because when it has been depressed far enough to cause shift of the carriage some perceptible resistance will be felt through 10 encounter of the pawl 35 with the ratchet 30 and unless the user desires to line-space he will not apply increased force to the key when this resistance is encountered. Obviously then this special key can be employed at will 15 for the purpose of causing the carriage to jump from one columnar position to another without stopping at intermediate positions otherwise determined by one or more of the fingers 4. Then, too, if a line-space is de- 20 sired at some other position of the carriage than its initial position that can be effected through full depression of the key with or without a columnar shift of the carriage, ac- 25 cording to whether the latter is permitted to move or is restrained. It may be restrained at any time by holding the hand lever. Then, as next to be described, special tabu- 30 lating stops coöperate with said handle to prevent movement of the carriage except when the handle is sprung slightly in a lateral direction.

Still referring to the handle arrangement shown by Figs. 1, 2, 3, 5, 6 and 7, there is fastened to the left side of the machine 35 casing, in addition to and associated with the aforesaid guide plate 22 for the index cards, a curved slotted plate 70. (As here shown the index holding plate is secured to this slotted plate.) A plain curved plate 40 71 is directly fastened to the casing of the machine by arms 71^a and the similarly curved plate 70 is secured to spacing posts 71^b carried by the plate 71 and receiving screws which serve to secure the index hold- 45 ing plate to the plate 70. The hand lever 13 extends up between the plates 70 and 71 and they are spaced apart sufficiently to permit limited lateral flexing of the lever which is made of comparatively thin steel 50 plate. This lateral flexing is for the purpose of engaging and disengaging said lever and the stops which may be employed for tabulating purposes. Each of these stops 55 comprises a beveled block 72 with a square boss 72^a to engage the slot of the plate 70 and a screw-threaded shank 72^b. The block is on the inner side of said plate and the said shank projects on the opposite side and receives a nut 73. A washer 74 is pref- 60 erably interposed between the nut and the side of the plate. Obviously in screwing up the nut will clamp the block in position and it will be prevented from turning by rea- 65 son of the engagement of its square boss with the sides of the slot. These stop pieces

can be adjusted and clamped in position anywhere along the slot, to suit the desired tabulation, and it will be noted that their location and arrangement is such as to make them very accessible so that a tool can be 70 readily applied to the nuts. For the pur- 75 poses of coöperation with said stop pieces, the hand lever 13 has a stop lug 13^a fastened against its outer side and here shown as of circular outline with a squared off dia- metrical shoulder 13^b and a beveled surface 13^c to one side of said shoulder for coö- 80 peration with the bevels of the stop pieces 72. In the particular construction under con- 85 sideration the beveled surface of the hand lever stop lug is forward and the beveled surfaces of the stop pieces or blocks 72 face rearward so that when the handle is pulled forward it may readily pass by the stop pieces, the beveled surfaces camming past 85 each other and the handle being flexed. It will be obvious, however, that no such action occurs in connection with shift of the carriage from right to left (corresponding with rearward swinging of the handle) for 90 the reason that the shoulder of the handle stop lug abuts against the squared front sides of the stop pieces. However, by slight pressure applied against the end of the handle of said lever the latter can be disengaged from any stop piece and the carriage thus released and permitted to move until 95 the lever strikes the next stop piece.

It will now be clear that the tabulation can be controlled entirely by the special 100 hand lever at the left of the machine. This has several advantages over control by the usual rock rod and stop fingers. With the index cards 23 located to correspond with the particular setting of the stop pieces, the 105 user can tell at a glance and without examining the work at all, just what the columnar position of the carriage is and can correspondingly shift it from any column to another at will, distributing items as called for by 110 the work in hand without having to leave his seat in front of the machine to examine the sheet in the holder of the paper carriage at the back of the machine. The hand lever is within easy reach so that back shifting 115 can be accomplished at any time and to any extent desired. The user is also enabled to line-space at any time he desires without necessarily driving the carriage all the way back home. Thus assuming that he desires 120 to back-shift only one column from the farthest column to the right when the machine is set up for printing three or more columns, the hand lever will simply be pulled far enough to shift the carriage back 125 to this desired columnar position and the carriage will be held at that position by contact of the shoulder of the handle lug against the stop piece. Assuming that the user desired to then print again in the 130

farthest column to the right, and so to line space, all he needs to do is to fully depress the key 50. While this rocks the tabulating bail on the carriage the latter will not shift because it is not being held by one of the fingers on the rod 3 but by one of the stop pieces 72. It will be understood of course that when using these stop pieces for tabulating purposes, the fingers 4 will be out of use, either set off out of range of the carriage movement or removed altogether from the rod, though one or more of these stop fingers may be used at the same time as one or more of the stop pieces 72, *e. g.*, for columnar positions intermediate those determined by the stops 72.

Passing now to the modified construction illustrated in Figs. 12 and 13, this pertains chiefly to the employment of a left side carriage handle without any of the tabulating functions such as that of the hand lever shown in the preceding views through the coöperation of its stop lug with the stop pieces 72. The hand lever 90 shown in Figs. 12 and 13 is not equipped with any stop lug and no provision is made for lateral flexing of this handle. Two plain guide plates or bars 91 and 92 are employed spaced apart only far enough to permit free swinging of the handle between them as guides. The index holding plate 22 is preferably used in this construction for the purpose of enabling the user to regulate back spacing of the carriage through operation of the hand lever. In this modified construction the lever is reversed as compared with that shown in the preceding figures, in that its rearward throw retracts the carriage against the latter's spring. Thus instead of the arrangement of segmental gears shown in the preceding figures, there is a single segment 94 fastened to the boss of the hand lever 90 and this single segment meshes directly with the spur gear 18. Obviously in this modified construction the hand lever steps forward as the carriage shifts from right to left. When a series of items has been printed along a horizontal line the user, seated in front of the machine, can conveniently return the carriage by throwing the hand lever rearward, and as in the construction before described, line-spacing will occur as a result of the return of the carriage to its initial position. However, the user may if he desires drive the carriage only part way back and, with the cards 23 set to correspond with the location of the stop fingers 4 on the tabulating rock rod 3, he can back shift the carriage very readily to any columnar position he desires.

I have here shown my invention applied to a style of Burroughs machine using what is known as a "split and normal platen", that is to say a platen comprising different sections each with its own line-spacing devices.

Such a construction has been made the subject of my application No. 714,822, filed August 13, 1912, and it may be very advantageously employed in conjunction with the character of tabulating means which is the subject of my present application. For an earlier type of sectional platen construction reference may be had to Patent No. 968,005 issued August 23, 1910, on the invention of Jesse G. Vincent. This, however, does not disclose coupling and uncoupling means for the platen sections as does my said application No. 714,822, which feature may be advantageously employed in the machine of the present application.

I claim:

1. In a machine of the class described, the combination of recording mechanism; a laterally shiftable paper carriage; a spring for shifting it one way; a handle reciprocating at right angles to said carriage and geared thereto for returning it; and tabulating stops for the carriage coöperating directly with said handle, the latter being flexible for lateral displacement to disengage it from the stops.
2. In a machine of the class described, the combination of recording mechanism; a laterally shiftable paper carriage; a spring for shifting it one way; a handle reciprocating at right angles to said carriage; a slotted bar along which said handle moves; and adjustable stops fitted to said bar, the handle being flexible for lateral displacement to disengage it from the stops.
3. In a machine of the class described, the combination of recording mechanism; a laterally shiftable paper carriage; a spring for shifting it one way; a reciprocating handle connected to said carriage for returning it and which moves backwardly and forwardly along one side of the machine; and an indexing guide adjacent the path of said handle.
4. In a machine of the character described, the combination of recording mechanism; a laterally shiftable paper carriage; a spring for shifting it one way; a reciprocating handle geared thereto for returning it; tabulating stops for the carriage coöperating with said handle; a second series of tabulating stops; and means for releasing the carriage from said last-mentioned stops.
5. In a machine of the character described, the combination of recording mechanism; a laterally shiftable paper carriage; a spring for shifting it one way; a reciprocating handle geared thereto for returning it; tabulating stops for the carriage coöperating with said handle; other tabulating stops carried by the carriage; and a key and connections for releasing the carriage from said last-mentioned stops.
6. In a machine of the character described, the combination of recording mechanism; a

- laterally shiftable paper carriage; a spring for shifting it one way; a reciprocating handle geared thereto for returning it; tabulating stops for the carriage coöperating with said handle; a rock-shaft upon said carriage; a series of tabulating stops carried by said rock shaft; and a key and connections for oscillating said rock-shaft to release the carriage from such last-mentioned stops.
- 5 7. In a machine of the character described, the combination of recording mechanism; a laterally shiftable paper carriage; a spring for shifting it one way; a reciprocating handle geared thereto for returning it; tabulating stops for the carriage coöperating with 35 said handle; a rock shaft upon said carriage; a series of tabulating stops carried by said rock-shaft and arranged to release the carriage when the shaft is given a limited 40 rocking movement; line spacing mechanism upon the carriage arranged to be operated by an excessive movement of the rock-shaft; and means for oscillating said shaft.
- 10 8. In a machine of the character described, the combination of recording mechanism; a laterally shiftable paper carriage; a spring for shifting it one way; a reciprocating handle geared thereto for returning it; tabulating stops for the carriage coöperating with 45 said handle; a rock shaft upon said carriage; a series of tabulating stops carried by said rock-shaft and arranged to release the carriage when the shaft is given a limited 50 rocking movement; a platen upon the carriage; line-spacing mechanism intermediate said rock-shaft and platen arranged to turn the latter when the shaft is given excessive movement; and a key and connections for 55 oscillating said shaft.
- 15 9. In a machine of the character described, 40 the combination of recording mechanism; a laterally shiftable paper carriage; a spring for shifting it one way; a reciprocating handle geared thereto for returning it; tabulating stops for the carriage coöperating with 45 said handle; a rock shaft upon said carriage; a series of tabulating stops carried by said rock-shaft and arranged to release the carriage when the shaft is given a limited 50 rocking movement; a platen upon the carriage; line-spacing mechanism intermediate said rock-shaft and platen arranged to turn the latter when the shaft is given excessive movement; manually-operated means for oscillating said shaft; and means operated by 55 the carriage in its return movement for giving said rock-shaft excessive movement.
- 20 10. 8. In a machine of the character described, the combination of recording mechanism; a laterally shiftable paper carriage; a spring for shifting it one way; a reciprocating handle geared thereto for returning it; tabulating stops for the carriage coöperating with 45 said handle; a rock shaft upon said carriage; a series of tabulating stops carried by said 50 carriage when the shaft is given a limited 55 rocking movement; a platen upon the carriage; line-spacing mechanism intermediate said rock-shaft and platen arranged to turn the latter when the shaft is given excessive movement; manually-operated means for oscillating said shaft; and means operated by the carriage in its return movement for giving said rock-shaft excessive movement.
- 25 11. 8. In a machine of the character described, the combination of recording mechanism; a laterally shiftable paper carriage; a spring for shifting it one way; a reciprocating handle geared thereto for returning it; tabulating stops for the carriage coöperating with 45 said handle; a rock shaft upon said carriage; a series of tabulating stops carried by said 50 carriage when the shaft is given a limited 55 rocking movement; a platen upon the carriage; line-spacing mechanism intermediate said rock-shaft and platen arranged to turn the latter when the shaft is given excessive movement; manually-operated means for oscillating said shaft; and means operated by the carriage in its return movement for giving said rock-shaft excessive movement.
- 30 12. 8. In a machine of the character described, the combination of recording mechanism; a laterally shiftable paper carriage; a spring for shifting it one way; a reciprocating handle geared thereto for returning it; tabulating stops for the carriage coöperating with 45 said handle; a rock shaft upon said carriage; a series of tabulating stops carried by said 50 carriage when the shaft is given a limited 55 rocking movement; a platen upon the carriage; line-spacing mechanism intermediate said rock-shaft and platen arranged to turn the latter when the shaft is given excessive movement; manually-operated means for oscillating said shaft; and means operated by the carriage in its return movement for giving said rock-shaft excessive movement.
